UNITED STATES PATENT OFFICE.

SAMUEL K. PLANK, OF HOUSTON, TEXAS.

DARBY.

1,227,308.

Specification of Letters Patent.

Patented May 22, 1917.

Application filed June 17, 1916. Serial No. 104,276.

To all whom it may concern:

Be it known that I, SAMUEL K. PLANK, a citizen of the United States, residing at Houston, in the county of Harris and State 5 of Texas, have invented certain new and useful Improvements in Darbies; and I do hereby declare the following to be a full, clear, and exact description of the invention, such as will enable others skilled in 10 the art to which it appertains to make and use the same.

This invention relates to a plasterer's darby, and the primary object of the invention is to provide a darby which is made 15 up of a plurality of detachable sections, whereby the sections may be disconnected for shortening the length of the darby for facilitating its transportation from place to place, and also whereby one of the sections 20 of the darby may be employed in close places, such as in closets or other places where the use of a full length darby is inconvenient.

With the foregoing and other objects in 25 view this invention consists in such novel features of construction, combination and arrangement of parts as will be hereinafter more fully described, illustrated in the accompanying drawing and claimed.

30 In describing the invention in detail reference will be had to the accompanying drawing wherein like characters designate like and corresponding parts throughout the several views, and in which:—

35 Figure 1 is a perspective view of the darby.

Fig. 2 is a side elevation of the darby showing parts in section.

Fig. 3 is a section on the line 3—3 of 40 Fig. 2, and

Fig. 4 is a side elevation of one of the joints of two of the sections showing them spread or separated.

Referring more particularly to the drawing, 1 designates the darby structure as an 45 entirety, which is composed of a plurality of sections, preferably three sections as indicated at 2, 3 and 4, comprising a center section 3 and the two end sections 2 and 4.

50 The end section 2 has a handle 5 attached thereto in the usual manner. The various sections 2, 3 and 4 include blades 5 having straight edges and an outer smooth surface, and ridges 6 which are composed of 55 sheet metal and are substantially circular

shaped in cross section. The ridges 6 have downwardly extending legs 7 formed thereon which engage and are secured to the upper surface of an attaching plate 8 as clearly shown in Figs. 1 and 3 of the drawing. The ridges 6 of the end sections 2 and 4 have tubes 8 positioned therein and projecting outwardly therefrom for telescopic mounting in the ridges 6 of the intermediate section 5, for connecting the end sections 2 and 4 to the intermediate section 3. The blades 5 of the intermediate section 3 project beyond the end of the ridge 6 thereof, and the inner ends of the blades 5 of the outer sections 2 and 4 are cut shorter 70 than the ridge, as clearly shown in Fig. 1 of the drawing, so that if it is desired, the center section 3 may be used independent of the end sections 2 and 4 for work in close places, such as in closets or the like. 75

In reducing the invention to practice, certain minor features of construction, combination and arrangement of parts may necessitate alterations to which the patentee is entitled provided such alterations are 80 comprehended within the scope of what is claimed.

What is claimed is:—

In a plasterer's darby, a center section, and end sections, said center and end sections comprising plates, ridges connected to said plates and being hollow, tubes carried by the ridges of the end sections and telescopically mounted in the ridge of the center section for detachably connecting the 90 end sections to the center section, blades carried by each of said sections, the inner ends of the blades of said end sections stopping short of the ridges carried thereby, clamping plates for clamping said ridges 95 to said blades, the portions of said clamping plates facing the ends of said center section extending beyond the ends of the blades of the end sections for gripping the protruding end of the blade of the intermediate section, 100 the end of the blade of said intermediate section projecting outwardly from the end of the ridge and clamping plates carried thereby.

In testimony whereof I affix my signature 105 in presence of two witnesses.

SAMUEL K. PLANK.
